(57) **CLAIM**

We claim the ornamental design for a cutting torch, as shown and described.

DESCRIPTION

FIG. 1 is a front, top, left side perspective view of a cutting torch showing our new design in a storage configuration; FIG. 2 is a top view thereof, the bottom view, left side view, and right side view being identical;

FIG. 3 is a rear view thereof;

FIG. 4 is a front view thereof;

FIG. 5 a front, top, left side perspective view of a cutting torch showing our new design in an in-use configuration;

FIG. 6 is a left side view thereof, the right side view being identical;

FIG. 7 is a top view thereof, the bottom view being identical;

FIG. 8 is a rear view thereof; and,

FIG. 9 is a front view thereof.

1 Claim, 4 Drawing Sheets
